Sam'l D. Vose, of Albany, N.Y.
Letters Patent No. 706. Dated. May 29th 1855
Filed-dated April 9th 1855.

The schedule referred to in these Letters Patent, and making part of the same.

To all whom it may concern.

Be it known that I, Sam'l D. Vose, of Albany County of Albany, and State of New York, have invented a new and useful design for an ornamental Cooking Stove and I do hereby declare the following to be a full and exact description, reference being had to the annexed drawings affixed to and making part of this specification.

The nature of my invention is such as cannot be easily described in words, but can be clearly understood from the drawings. The invention or new design referred to is made up from a combination of figures and ornaments on the outer plates or surface of the stove.

The following plates, designated by letters, are those which embrace the combination, or design spoken of.

Letter T represents the top of the Stove.

" F " front and front door of the stove.

" H " Hearth of the stove.

" S " " Side and side doors of the stove

" L " " Legs of the stove,

I do not claim any separate part of the configuration.

What I claim as my invention and desire to secure by
Letters Patent is the arrangement and combination of the several
figures and mouldings, the whole forming an ornamental de-
sign for a cooking Stove.
